SAFETY RELEASE FOR WRINGERS

John Mikulasek, Newton, Iowa, assignor to The Maytag Company, Newton, Iowa, a corporation of Delaware

Application December 20, 1934, Serial No. 758,409

13 Claims. (Cl. 68—263)

This invention relates to wringers and more particularly to the provision of a safety release positioned in an accessible place for quick manipulation by the operator to release the pressure between the rolls.

As is well known, in the use of wringers it is sometimes necessary for the operator to be able to quickly release the pressure between the rolls as, for example, in cases when the operator's fingers, clothing, or the like, get caught between the rolls.

Among the objects of the present invention is to provide a safety release for wringers of such nature that it may be operated by either pushing or pulling upon the operating member and be quick and effective in operation to relieve the pressure between the rolls.

Another object is to provide in a safety release for wringers an operating portion so positioned as to be most accessible to be grasped by the operator for immediate operation to relieve the pressure between the rolls.

A further object is to provide a safety release for wringers which is quick in operation to relieve the pressure between the rolls and permits ready and easy reapplication of the pressure between the rolls when it is desired to return the parts to operating position.

A still further object is to provide improved means for positively and firmly holding the rolls together with the desired pressure and also permit the instant release of this pressure and separation of the rolls when desired.

Another object is to provide such apparatus that will be neat in appearance, economical of manufacture and provide the maximum of safety for the operator.

Other objects, advantages and capabilities will hereinafter more fully appear.

My invention further resides in the combination, construction and arrangement of parts illustrated in the accompanying drawings, and while I have shown therein a preferred embodiment I wish it understood that the same is susceptible of modification and change without departing from the spirit of my invention.

In the drawings—

Fig. 1 is a side elevation of a wringer with my improved safety release applied thereto.

Fig. 2 is an end elevation looking toward the right-hand side of Fig. 1.

Fig. 3 is a fragmentary perspective view of a portion of one end of a wringer having my invention applied thereto, parts being broken away

and parts being shown in section for the sake of clearness.

Fig. 4 is a fragmentary vertical longitudinal section through an end portion of a wringer showing my invention applied thereto, the section being taken in a vertical plane passing through the longitudinal axes of the upper and lower rolls, these rolls and the operating plate at the top, however, being shown in elevation for the sake of clearness.

Fig. 5 is a vertical transverse section taken on the line 5—5 of Fig. 4 and looking in the direction of the arrows, and showing the parts in position to apply pressure between the rolls.

Fig. 6 is a fragmentary view similar to Fig. 5 but showing the parts in position to release the pressure between the rolls.

Fig. 7 is a side elevation of the lever through which pressure is applied between the rolls and showing a modified form of nose portion.

Referring more in detail to the drawings, I have shown my safety release for wringers applied to a wringer of the split type. However, I wish it understood that the same may be applied to other types of wringers wherever applicable.

The wringer shown in the drawings comprises the main lower frame A and the upper auxiliary frame indicated generally at B. The main frame A, which is suitably mounted for swinging in a horizontal plane, has rotatably mounted therein the lower wringer roll 1, while the auxiliary frame B has rotatably mounted therein the upper roll 2. At each end of the main frame and slidably mounted in its interior is a pair of rods 3 and 4, each of which is urged downwardly by a coil spring 5, bearing at its upper end against the seat 6 and at its lower end against the nut 7, these springs, each being under compression, the amount of which compression may be adjusted by turning nut 7. Rod 3, of which there is a similar rod at the other end of the main frame and on the same side of the wringer, is formed at its upper end with a hook portion 8 having a laterally extending projection 9 and an enlarged portion 10, which when the pressure between the rolls is relieved bears against the resilient washer 11, but which when pressure is applied between the rolls stands a slight distance away from this washer.

Rod 4 is similar in construction to rod 3 except it is provided at its upper end with a head portion 12, having formed therein an opening 13 for receiving pin 14 for pivotally mounting thereto the bearing cap 15, there being one of these bearing caps and a bolt 4 at each end of the wringer.

and upon the opposite side from rods 3, so that when the pressure between the wringer rolls is released the upper auxiliary frame B may be swung upwardly and backwardly away from the main frame A to separate the rolls from each other, as shown in dotted lines of Fig. 6.

Formed integrally with each of the bearing caps 15 is an upstanding portion 16, in which is rotatably mounted the circular end 17 of the upper standing operating plate 18. Eccentrically fixed to the end portion or trunnion 17 of plate 18 by means of a stud bolt, or the like 19, is a roller 20 for a purpose more fully hereinafter set forth. This roller 20 due to its being eccentrically mounted with relation to trunnion 17 will move laterally in either direction depending upon which direction plate 18 is swung. Also pivoted in the bearing cap 15 at 21 is lever 22, which is generally in the form of a bell-crank and is formed at its outer end with a nose portion 23 adapted to take under and lift to a certain extent projecting lip 9 of head 8 of rod 3. At its opposite end lever 22 is formed with a projecting arm 24, which in its upper face is provided with a notch 25 in which roller 20 is adapted to be seated when plate 18 stands in or approximately in a vertical position, as shown in solid lines in Fig. 5.

In the lower face of extended arm 24 of lever 22 is an opening in which is seated a coil spring 26, the other end of which spring seats in a corresponding opening in the adjacent portion of bearing cap 15. This spring 26 presses arm 24 of lever 22 upwardly when roller 20 has been moved away from contact with arm 24. This upward pressure of spring 26 causes nose 23 of lever 22 to move downwardly and inwardly away from contact with the hook lip 9 when roller 20 is out of contact with arm 24, which latter position these parts will occupy when the pressure between the rolls has been released. As shown in Fig. 5, nose 23 of lever 22 is formed integral with the lever. A modification of this is shown in Fig. 7, in which the nose of lever 22 is formed with a roller 23a to contact with the under face of the hook lip 9 of rod 3 when pressure is applied between the two rolls.

Each of bearing caps 15 is provided on its upper portion with a cover 27 to house the lever 22 and associated parts for protection from dirt and the like.

As seen from the above, the pair of tension rods 4 act as tension hinge rods, while the pair of tension rods 3 act as tension hook rods. The moving of these rods slightly upwardly, as shown in Fig. 5, will, due to the compression of the springs 5, act in an obvious manner to apply pressure between the rolls. The rolls will at their ends be provided with the usual ball-bearings or other anti-friction means as desired. The release lever or plate 18 is journaled at each end, as described above, in the bearing caps 15, respectively, and extends substantially the full length of the wringer. The release plate 18 is also provided at each end with a rubber cap, roller, or the like 28, which, when the release plate 18 has been swung to its limit of movement on either side of the cover plate 27, will strike the bearing cap and silently stop further movement of the release plate 18 without marring or scratching cover 27. As shown in the drawings, release plate 18 extends upwardly a substantial distance above the trunnion 17, thus affording considerable leverage when its upper edge is grasped by the hand of the operator.

The operation of my safety release for wringers will be understood from the above, and from which it will be seen that when the release plate 18 stands in a vertical or approximately vertical position, as shown in Fig. 5, the arm 24 of lever 22 will be pushed downwardly and held in that position by roller 20 seating in notch 25. When in this position the nose 23 of lever 22 will be under the hook projection 9, thus holding rods 3 in a slightly elevated position, which will result in causing pressure between the upper and lower rolls. This pressure will also be augmented by the fact that heads 12 of rods 4 likewise are elevated a slight distance above the adjacent portion of the main frame A, thus transmitting the compression of springs 5 to the rolls. Should any of the operator's fingers, clothing, or the like, become caught between the rolls all that is necessary for the operator to do is to either push or pull the upper portion of plate 18, which will swing roller 20 laterally away from the notch 25 to a position where the wringer forces and spring 26 will move arm 24 of lever 22 upwardly and cause nose 23 to move downwardly and inwardly away from hook lip 9, thus instantly relieving the pressure between the two rolls and permitting, if desired, the upper auxiliary frame to be swung upwardly to the position shown in dotted lines in Fig. 6 (or farther if desired) to separate the rolls from each other.

The engagement between the lever nose 23 and the hook lip 9 when applying pressure between the rolls is further facilitated by holding the head 8 against lateral slipping by reason of the slotted guide 29 and shoulder 30, these parts being formed as shown in bearing cap 15. When the plate 18 is swung in either direction (by either pushing or pulling upon its upper edge) the roller 20 will be swung away from contact with arm 24 of lever 22, after which arm 24 will be held upwardly by spring 26, thus moving nose 23 away from engagement with hook lip 9, which will allow the hook of the tension rod 3 to enter freely the guide slot in the bearing cap 15 during closing operation of the auxiliary frame B.

By constructing the parts in such manner as to permit operation by either a pushing or pulling movement on the upper portion of plate 18, I have made possible a quick and effective operation of my safety release by reason of eliminating any possible confusion on the part of the operator which might result if plate 18 were to be operated in only one direction. This adds greatly to the safety of the operator who, even if both hands were caught between the rolls, could release herself by bending forward and pushing plate 18 sidewise with her body.

Having now described my invention, I claim:

1. In a wringer a main frame having a lower roll and roll pressure means, an upper frame carrying an upper roll, said upper frame being pivotally connected to the main frame and capable of being swung upwardly to separate the rolls, the pressure means on the main frame having a hook portion at each end of the main frame, a lever at each end of the upper frame and pivoted thereto, each lever having a projection to move under one of said hook portions or be moved free therefrom, and a swinging operating member fulcrumed in the respective ends of the upper frame, said operating member having at each end an eccentrically positioned projection movable against that portion of the adjacent lever that is on the opposite side of the pivot.

from the hook to move the lever projection under the hook portion to lift the same and apply pressure between the rolls, the operating member when swung in one direction from its mid-position moving the eccentrically positioned projection away from pressure-applying position to free the projection from the hook and relieve the pressure between the rolls, and when swung in the other direction accomplishing the same result.

2. In a wringer having an upper and a lower frame, a pair of rolls and pressure means for applying pressure between the rolls, a safety release for quickly relieving the pressure between the rolls, said safety release comprising an upstanding plate extending longitudinally of the wringer and having its ends pivotally mounted in the respective ends of the upper frame, and connecting means between the plate and pressure means whereby the pressure between the rolls will be quickly relieved upon swinging the plate in either direction, said pressure means comprising a spring-pressed rod having a lateral projection formed on its upper end, and said connecting means comprising a lever having a fulcrum and a nose movable under said lateral projection to apply and relieve the pressure between the rolls depending upon the direction of movement of the lever, said pivotally mounted plate having a projection eccentric to the pivotal axis of the plate, said projection contacting the lever to hold the lever nose under the lateral projection when the plate stands in one position and to permit it to move therefrom when the plate is swung in either direction, said swinging of the plate in either direction from mid-position also permitting separation of the rolls.

3. In a wringer having a main and an auxiliary frame, a pair of rolls and pressure means for applying pressure between the rolls, a safety release for quickly relieving the pressure between the rolls, said safety release comprising an upstanding plate extending longitudinally of the wringer and having its ends pivotally mounted in the respective ends of the auxiliary frame, and connecting means between the plate and pressure means whereby the pressure between the rolls will be quickly relieved upon swinging the plate in either direction, said pressure means comprising a spring-pressed rod having a lateral projection on its upper end, and said connecting means comprising a lever having a fulcrum and a nose movable under the lateral projection to apply and relieve the pressure between the rolls depending upon the direction of movement of the lever, said pivotally mounted plate having a projection eccentric to the pivotal axis of the plate, said projection contacting the lever to hold the lever nose under the lateral projection when the plate stands in one position and to permit it to move therefrom when the plate is swung in either direction, and means for holding said lever nose away from the lateral projection when the plate is swung away from said one position, the swinging of the plate in either direction from mid-position also permitting separation of the rolls.

4. In a wringer a main frame having a roll and roll pressure means mounted therein, said pressure means comprising two pairs of spring-pressed rods vertically slidable in the main frame, an auxiliary frame pivotally connected with the upper ends of one pair of the rods, each of the other pair of rods having a hook on its upper end, said auxiliary frame having a lever fulcrumed in

each end thereof, each of said levers having a nose engageable under the adjacent hook, a roll mounted in the auxiliary frame, said auxiliary frame comprising a longitudinally extending plate rotatably journaled in the ends thereof, the journals of said plate each carrying an eccentrically mounted projection normally in contact with the adjacent lever to hold the lever noses under the hooks to slightly raise the corresponding rods to hold the rolls together under pressure, said lever noses being freed from contact with the hooks and the rolls being separable when the plate is swung laterally in either direction.

5. In a wringer of the split type having a main frame and an auxiliary frame pivotally mounted at the opposite ends of the main frame for swinging movement about said spaced pivots, each of the frames having a roll mounted therein, means for applying pressure between the rolls, an upstanding plate extending longitudinally along the top of and fulcrumed in the auxiliary frame, a pair of levers fulcrumed one in each end of said auxiliary frame adapted to be operated by the plate and operatively connected with the pressure applying means, the fulcrums of the levers being separate and distinct from the fulcrum of the upstanding plate, said plate, levers and pressure means being so related that when the plate stands in vertical position the rolls will be pressed together and when the plate is swung in either direction away from the vertical position the pressure between the rolls will be relieved and the rolls may be freely moved apart.

6. In a wringer a main frame carrying a roll and a pair of spring-pressed rods, said rods being longitudinally slidable in the main frame, an auxiliary frame pivotally mounted with relation to the main frame, the upper end of each of the rods being formed with a hook, a roll in the auxiliary frame, a pair of levers pivotally mounted one on each end of the auxiliary frame, each of the levers having a nose engageable under the adjacent hook, a plate mounted on the auxiliary frame for swinging in either direction and having means engaging each of the levers to move the levers to apply pressure between the rolls or release the pressure, and means for moving the lever noses away from the hooks when the plate is swung in either direction away from pressure applying position.

7. In a wringer a main frame having a lower roll and roll pressure means, an upper frame carrying an upper roll, said upper frame being pivotally connected to the main frame for swinging upwardly to separate the rolls, the pressure means including an upstanding portion at each end of one side of the main frame, each of the upstanding portions having a laterally extending projection, a lever at each end of the upper frame and pivoted thereto, each lever having a nose portion adapted to be moved under one of said projections or be moved free therefrom, a swinging operating member having its ends rotatably journaled in the respective ends of the upper frame, the journaled portions of the operating member having a projection eccentric to the pivotal axis of the operating member, each of said eccentric projections being at its lowermost point of travel when the operating member stands vertical, the eccentric projections at this time each bearing downwardly on the free end portion of its corresponding lever to elevate the lever nose portion and move the latter under the adjacent laterally extending projection to raise the same and apply the pressure in the pressure means.

- to create a corresponding pressure between the rolls.
8. In a wringer a main frame having a lower roll and roll pressure means, an upper frame carrying an upper roll, said upper frame being pivotally connected to the main frame for swinging upwardly to separate the rolls, the pressure means including an upstanding portion at each end of one side of the main frame, each of the 10 upstanding portions having a laterally extending projection, a lever at each end of the upper frame and pivoted thereto, each lever having a nose portion adapted to be moved under one of said projections or be moved free therefrom, a swinging operating member having its ends rotatably journaled in the respective ends of the upper frame, the journaled portions of the operating member having a projection eccentric to the pivotal axis of the operating member, each of said 15 eccentric projections being at its lowermost point of travel when the operating member stands vertical, the eccentric projections at this time each bearing downwardly on the free end portion of its corresponding lever to elevate the lever nose portion and move the latter under the adjacent laterally extending projection to raise the same and apply the pressure in said pressure means to create a corresponding pressure between the rolls, the eccentric projections each being slidably movable in either direction on its corresponding free end portion of the lever, the swinging of the operating member in either direction freeing the nose portion from the laterally extending portion and permitting the swinging of the upper frame 20 to open position.
9. In a wringer a pair of frames, one of the frames being pivotally connected to the opposite ends of the other frame for swinging movement about the pivots, each frame carrying a roll, one 25 of said frames having a roll pressure means, the other frame having means for applying pressure to the pressure means and for releasing the same, said pressure applying and releasing means comprising a pair of levers each having releasable engagement with the roll pressure means, a swingable bar extending longitudinally of the wringer, and connections between the bar and the pair of levers to hold the rolls together under pressure when in one position and to relieve the 30 pressure and permit separation of the rolls when the bar is swung in either direction away from said position, said levers each being fulcrumed on a bearing separate and distinct from the fulcrum bearing of the bar.
10. In a wringer having a pair of rolls and pressure means for applying pressure between the rolls, a safety release for quickly relieving the pressure between the rolls, said safety release comprising an upstanding member extending longitudinally of the upper portion of the wringer and having its ends pivotally mounted in the respective ends of the wringer, and connecting means between the safety release and the pressure means whereby the pressure between the 35 rolls will be quickly relieved upon swinging the safety release in either direction, said pressure means comprising a spring-pressed rod having a lateral projection formed on its upper end, and said connecting means comprising a lever having a free end, a nose and an intermediate fulcrum, the pivotal mounting of the safety release having projecting means for contacting the free end of the lever to positively force the nose under the lateral projection of the pressure rod to apply 40 pressure between the rolls when the safety re-
- lease is moved into a predetermined position, and relieve the pressure between the rolls by swinging the safety release in either direction from said predetermined position.
11. In a wringer a main frame carrying a roll and two pairs of spring-pressed rods, said rods being longitudinally slidtable in the main frame, an auxiliary frame pivoted to the upper end of each of the rods of one of said pair, the upper end of each of the rods of the other pair being 45 formed with a hook, a roll in the auxiliary frame, a pair of levers fulcrumed one in each end of the auxiliary frame, each of said levers having a nose engageable under the adjacent hook to lift the corresponding rod and apply pressure between 50 the rolls, an upstanding member extending longitudinally along the top of the auxiliary frame and pivoted at its ends in the ends of the latter, each end of the upstanding member having a projection engaging the free end of the adjacent lever for moving its other end to positively push its nose under its corresponding hook for lifting the latter and applying pressure between the rolls when the upstanding member is moved to a predetermined position, said pressure being quickly 55 relieved and the rolls freely movable apart when the upstanding member is swung in either direction from said predetermined position.
12. A safety release for wringers comprising a frame having separable upper and lower parts in 60 each of which parts is mounted a roll, a lever pivotally mounted at each end of the upper part, pressure means for applying pressure between said rolls, said pressure means being formed with latching heads each having an angular portion, a 65 projecting portion on one end of each of the levers adapted to be held under one of the angular portions to apply pressure to the rolls when the levers are rotated in one direction, and a release member extending longitudinally of the wringer along 70 the upper part, said member being pivoted on said upper part and having portions contacting the levers so that said projecting portions will be moved away from engagement with the angular portion upon swinging movement of the release member in either direction to release the pressure 75 between the rolls, each of the levers having a free end, said projecting portion and an intermediate fulcrum, said contacting portions of the release member engaging the free ends of the levers to 80 positively push said projecting portion under said angular portion of the latching heads.
13. In a wringer a main frame having a lower roll, an upper frame pivotally connected with said lower frame and carrying an upper roll, a pair of 85 pressure rods in the main frame, each of said rods having a hook at its upper end, a release bar extending along the upper side of the upper frame and fulcrumed in the ends of the latter, a lever fulcrumed in each end of the upper frame, the 90 fulcrums of said levers being separate and distinct from the fulcrums of said release bar, each of said levers having a free end and a nose with the fulcrum of said levers located intermediate 95 the free end and nose, and a projection on each of the fulcrums of the release bar engaging the free ends of the levers respectively to positively push said noses under said hooks and raise the same to apply pressure between the rolls when 100 the release bar is swung to a predetermined position and to release said pressure when the release bar is moved either way from said predetermined position.
